UNITED STATES PATENT OFFICE.

LYSANDER E. WRIGHT, OF EAST ORANGE, AND HENRY B. COSTANTIN, OF CLIFTON,
NEW JERSEY.

DESIGN FOR A TIRE.

Application filed November 19, 1925. Serial No. 15,474. Term of patent 7 years.

To all whom it may concern:

Be it known that we, LYSANDER E. WRIGHT and HENRY B. COSTANTIN, both citizens of the United States, and residents, respectively, of East Orange, in the county of Essex and State of New Jersey, and Clifton, in the county of Passaic and State of New Jersey, have invented a new, original, and ornamental Design for Tires, of which the following is a specification, reference being had to the accompanying drawing, forming part thereof.

Figure 1 is a face view of a portion of the tread of an automobile tire of our improved design, and

Figure 2 is a cross-section of the same as on line 2—2, Fig. 1.

We claim:

The ornamental design for a tire, as shown.

LYSANDER E. WRIGHT.
HENRY B. COSTANTIN.
